UNITED STATES PATENT OFFICE.

FERDINAND THUN, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

CORD-BRAIDING MACHINE.

No. 898,938.

Specification of Letters Patent. Patented Sept. 15, 1908.

Application filed August 12, 1905. Serial No. 273,850.

To all whom it may concern:

Be it known that I, FERDINAND THUN, a citizen of the United States, residing in Wyomissing, Berks county, Pennsylvania, have invented certain new and useful Improvements in Cord-Braiding Machines, of which the following is a specification.

My invention relates particularly to the manufacture of flexible electric conductors, such as telephone-cords in which the wire or wires form the cores of an inclosing braiding for a portion of their length and are freed from the braiding for another portion of their length.

15 The main object of my invention is to provide for continuously forming a braid alternately around and free of a continuous core or cores without taking out or disturbing the core, and further to provide for making the successive alternate empty braid portions of greater length if desired than the corresponding free core portion, so as to produce a continuous cord consisting of a continuous core alternately inclosed in a continuous braiding 25 and free therefrom and with the empty portion of the braiding of greater length than the corresponding free core portion so that when cut into separate cords a braided terminal tie-cord will be provided of greater 30 length than the free terminal core.

In the accompanying drawings illustrating my invention Figure 1 represents a known form of telephone cord having the terminal portions of two conductors freed from the braid inclosing their main portion and such braid continued independently of the free core terminal to form a tie-cord of greater length than said core terminals. Fig. 2 is a diagram view showing my continuously 35 formed plural-cord product before being cut to form separate cords indicated in Fig. 1. Fig. 3 is a diagrammatic plan view of a braiding mechanism adapted to make such a product as above described, and Fig. 4 is an elevation of the same looking in the direction of the arrow 4, but showing the switch-cam and take-off mechanisms in different positions for clearness of illustration. Fig. 5 indicates a continuous single-conductor cord as 40 produced on my improved machine.

Heretofore telephone cords having tie-braid extensions of the braided core covering, such as indicated in Fig. 1, have been made by manipulating the core pieces by hand so as to move the terminal portions

thereof from the braid forming axis while the empty tie-braid was being formed. This method of production evidently requires constant attention instead of being automatic and continuous as provided for by my invention.

In the mechanism indicated 1 and 2 represent the usual top and bottom plates of a braiding machine, between which are mounted a circular series of drive-gears arranged to engage and traverse a series of bobbin carriers guided in intersecting serpentine race-ways formed in the top plate. The general construction and operation of this class of machines being well known only such parts thereof as are required to be shown and described in order to make clear the application of my improvements thereto, will be particularly referred to.

As indicated in Fig. 3 the intersecting serpentine race-ways are arranged so as to form different tubular courses for the carriers, a main course being provided in the usual outer series of intersecting race-circles, and what may be termed a cut-out carrier course being formed by providing an inner series of intersecting race-circles, marked 3, 4, and 5 respectively, on the portion of the figure to one side of the center *c* of the machine and duplicated at 3^a, 4^a, and 5^a, as shown, on the other side of said center. This inner series of intersecting race-circles is grouped around a vertical guide-way 6 through the top and bottom plates, which guide-way is provided for the passage of a continuous core 7 as hereafter described; and they connect both with the main race-circles 9, 9, which are common to both courses, and with the main race-circles 8, 8, which are exclusively outer course circles, so that by providing suitable switches 10 and 11 adapted to properly direct the carriers, the latter may be caused either to take the main outer course or to be diverted into the cut-out or inner course through the race-circles 3, 4, and 5. The effect of this novel arrangement of alternate courses, in connection with the core guide-way 6, is to enable the carriers to be passed either outside of or inside of a core 7 so as to form a continuous braid alternately inclosing and lying to one side of said core as desired. Referring to Fig. 4 it will be seen that a tubular extension 15 of each of the two vertical guide-ways 6 and 6^a shown in Fig. 3, is provided to carry the cords 7 and 7^a inward to the braiding

- center so that the braid may be formed either around or to the side of said cores according as the carriers are traversing the main course or the cut-out course as already described.
- 5 The braid, as formed, and the cores 7 sheathed thereby or unsheathed as the case may be, pass over the take-off wheel 16 as shown, the latter being suitably driven as desired.
- 10 The switches 10 and 11, and duplicates 10^a and 11^a as shown in Fig. 3, are operated as indicated by levers 20 pivoted at 21 and having their lower ends 22 connected by rods 23 to a rotatably mounted disk or plate 24 on 15 the bottom plate 2 of the machine, said disk being in turn connected by suitable rods to arms 27 on the switch axes 28, so that the respective switches will be turned to rightly direct the carriers as determined by the properly timed movement of the respective levers 20. The movements of the latter, as shown, are controlled by a pair of cam disks or wheels 30 mounted on a rotary shaft 31, each of said cam wheels being provided with properly spaced peripheral notches 33 and 33 which are adapted to permit the inward movement of the contacting portions of the levers by the action of springs 34, only when 25 said notches are turned into position to receive the projections 35 on said levers. These cam wheels 30 may be adjustably secured to the shaft 31 and the latter is rotated in any convenient manner with the carrier driving gears, through a worm shaft 32 and intermediate gears 36, 37, 38, and 39, as 30 shown; the double-gear 38—39 being preferably changeably mounted upon an adjustable arm 41 so as to permit the relative speed of rotation of the cam wheels 30 to be changed 35 for varying the lengths of the cords.
- To provide, as previously mentioned, for making the sections of empty braid which connect the integral core-sheathing sections, of greater length than the unsheathed portions of the core which form the connecting terminals of the separated cords in telephone service, I employ means for changing the relative take-off of the empty-braid portions. As indicated in Fig. 4 this purpose is 40 effected by a supplementary take-off cam 45 fixed to a suitably mounted shaft 46 which is operatively connected to the switch mechanism so as to operate in unison therewith; the take-off cam 45 being arranged to press the 45 empty-braid sections of the cord laterally during their formation to supplement the main take off 16, and to be out of action during the formation of the braid around the core.
- 60 By means of the improved braiding mechanism thus described and illustrated it will be seen that a plurality of telephone cords or the like may be automatically produced in continuous lengths or strips, the continuous core or cores being alternately covered by the

continuous fabric or free from the latter, and the empty portions of said continuous fabric being of equal or greater length as desired than the free core portions; so that such continuous cord may be cut to form separate 70 cords with terminal cores and tie-braids as may be desired. The travel of the bobbin carriers successively in the main outer course and in the cut-out or inner course, whereby the braiding is alternately effected around 75 the core or cores 7 and free of the latter, is automatically controlled as desired by the switch-operating mechanism; and the length of the empty braid sections relative to the free core portions is varied as desired by 80 means of the additional take-off 45 provided for such empty-braid sections.

In a slightly modified mechanism the duplicate cut-out race-circles 3^a 4^a and 5^a are omitted, the plural cores if desired being 85 passed through one passage-way 6, without material change in the operation or product. Fig. 5 illustrates a single-conductor cord made in accordance with my invention; such cord as shown corresponding with the core 90 cord 7 employed in duplicate in Figs. 1 and 2, but having the continuous braided fabric free from the wire at intervals, for a short distance, so as to permit the attaching of the terminal-points *c* to the wire without stripping off a portion of the braided covering as heretofore required. 95

Other modifications may be readily made without departing from the spirit of my invention.

What I claim is:—

1. A tubular braiding machine for telephone cords or the like having a main carrier course, a cut-out carrier course comprising a series of three or more additional race-circles the end ones only of which connect with the main course, a guide way for a continuous core cord located between said additional race-circles and the main carrier course, and switches at the connected race-circles substantially as set forth. 105

2. A tubular braiding machine for telephone cords or the like having a main carrier course, a cut-out carrier course comprising separate series of three or more additional race-circles, the end circles only of each of said series being connected with the main course, guide ways for separate continuous core cords located respectively between each series of additional race-circles and the main 110 course, and switches at the connected race-circles, substantially as set forth. 115

3. A tubular braiding machine for telephone cords or the like having a main carrier course and a core cut-out carrier course a 125 guide way for a continuous core cord located outside of said cut-out course switches for diverting the carriers at intervals from one to the other of said courses to form alternate core-covering braid portions and empty-

braid portions, and differential take-off mechanism for said portions whereby excess lengths of the empty braid portions are produced substantially as set forth.

5. A tubular braiding machine for telephone cords or the like having a main carrier course and a core cut-out carrier course, a guide way for a continuous core cord located outside of said cut-out course, switches for diverting the carriers at intervals from one to the other of said courses to form alternate core-covering braid portions and empty-braid portions, a main take-off, a supplementary take-off for the empty-braid portions, and means for throwing said supplementary take-off into action as required.
10. A tubular braiding machine for tele-

phone cords or the like having a main carrier course and a core cut-out carrier course a guide way for a continuous core cord located outside of said cut-out course, a switch mechanism for diverting the carriers from one to the other of said courses to form alternate core-covering braid portions and empty-braid portions, a main take-off, and a supplementary take-off for the empty braid portions operatively connected to said switch mechanism.

In testimony whereof, I affix my signature, in the presence of two witnesses.

FERDINAND THUN.
